United States Patent

Des. 238,411

Patented Jan. 13, 1976

238,411

BOTTLE OPENER

Sol J. Levenson, 2636 S. Belvoir Blvd.,
University Heights, Ohio 44118

Filed Aug. 23, 1974, Ser. No. 500,042

Term of patent 14 years

Int. Cl. D7—06

U.S. Cl. D8—18

FIG. 1 is a top plan view of a bottle opener showing my new design;

FIG. 2 is an elevational view looking from the line 2—2 of FIG. 1;

FIG. 3 is a bottom plan view thereof looking from line 3—3 of FIG. 2;

FIG. 4 is a cross-sectional view taken along line 4—4 of FIG. 1;

FIG. 5 is a cross-sectional view taken along line 5—5 of FIG. 3; and

FIG. 6 is a fragmentary view looking from line 6—6 of FIG. 3;

A cross-sectional view looking from line 5—5 in a direction opposite to the arrows shown on line 5—5 will be a mirror image view of FIG. 5.

I claim:

The ornamental design for a bottle opener, as shown and described.
